PRODUCE CARTON

Robert A. Bamburg, West Monroe, La., assignor to Olin Mathieson Chemical Corporation, a corporation of Virginia

Application November 25, 1957, Serial No. 48,626

Term of patent 14 years

(Cl. D58—12)

FIG - 2

Fig. 1 is a front perspective view of a produce carton showing my new design in a closed position; and,

Fig. 2 is a front perspective view thereof in the open position.

The rear and side, not shown, are substantially the same as the front and side, respectively, shown.

The characteristic features of my design for the produce carton disclosed reside in the groups of three slots on the sides and top portions of said carton in the position and relation shown.

I claim:

The ornamental design for a produce carton, substantially as shown and described.
